UNITED STATES PATENT OFFICE.

SAMUEL HODGINS, OF ST. LOUIS, MISSOURI, ASSIGNOR TO HIMSELF AND FERDINAND MEYER.

IMPROVEMENT IN GAITER-PATTERNS.

Specification forming part of Letters Patent No. 121,367, dated November 28, 1871.

To all whom it may concern:

Be it known that I, SAMUEL HODGINS, of St. Louis, in the county of St. Louis and State of Missouri, have made a certain new and Improved Mode of Cutting the Uppers of Gaiters; and I do hereby declare that the following is a full and true description thereof, reference being had to the accompanying drawing and to the letters of reference marked thereon.

The nature of this invention consists in cutting the leather to form the uppers for gaiters, as per the following mode or pattern now to be more fully described.

To enable those herein skilled to make and use my said invention, I will now more fully describe the same, referring to the accompanying drawing, of which—

Figure 1 represents a side elevation of my improved uppers for low gaiters; Fig. 2, a plan of my mode of cutting the leather for low gaiters; and Fig. 3, a part plan of same pattern for high gaiters.

The object being to form the same size of gaiters from a smaller piece of leather than heretofore done, the leather A is cut according to the pattern, plainly indicated in Figs. 2 and 3. Small openings a terminating in slits a' are thus formed at the instep part. The pattern thus cut is crimped to form the open full spaces required for the

rubbers B, and in doing this the right instep is also formed and the uppers receive the proper shape for the lasts.

It will be noticed that in saving the leather at the instep part less leather for the sides of the upper is required. As, however, in the usual well-known way of cutting gaiter-uppers the said instep part is cut out full to receive the rubbers a larger piece of leather is required for the lower ends of the uppers. Furthermore, by cutting the leather as shown in Figs. 1 and 2 a greater draft is obtained at line α α' ; the draft gained adapts the upper to fit better on the last. Also, a more perfect instep is achieved, as by the crimping action the instep can readily be formed; and, finally, an extra seam is dispensed with, as the entire back piece is gained either for high or low gaiters.

Having thus fully described my said invention, what I claim is—

The herein-described gaiter-pattern, having the instep part cut with the openings and slits a a', substantially as and for the purpose set forth.

In testimony of said invention I have hereunto set my hand.

Witnesses: SAMUEL HODGINS.
WILLIAM W. HERTEL,
FERD. MEYER.
